UNITED STATES PATENT OFFICE.

MAXIMILLIAN P. JANISCH, OF MUSKEGON, MICHIGAN.

CLOTHES-WRINGER.

SPECIFICATION forming part of Letters Patent No. 715,077, dated December 2, 1902.

Application filed April 30, 1902. Serial No. 105,381. (No model.)

To all whom it may concern:

Be it known that I, MAXIMILLIAN P. JANISCH, a citizen of the United States, and a resident of Muskegon, in the county of Muskegon and State of Michigan, have invented certain new and useful Improvements in Clothes-Wringers; and I do hereby declare that the following is a full, clear, and exact description thereof.

10 The invention consists in certain peculiarities of construction and combination of parts hereinafter particularly set forth with reference to the accompanying drawings and subsequently claimed, the object of said invention being to improve the details of clothes-wringers in which the upper rolls under pressure automatically adjust themselves to varying thickness of material operated upon without bind or increase of friction in the 20 gearing.

Figure 1 of the drawings represents a partly-sectional rear elevation of my improved clothes-wringer; Figs. 2, 3, and 4, partly-sectional views of the wringer, respectively indicated by lines 2 2, 3 3, and 4 4 in the first figure; and Fig. 5, a front elevation of a portion of the wringer.

Referring by letter to the drawings, A indicates the top bar; B, each of a pair of longitudinally-slotted standards; C, the name-board, and D the under drip-board or watershed, that combine to form the wood frame of my clothes-wringer, this frame being similar in the general construction and assembly 35 of its parts to those that are old in the art. Each standard B of the frame is provided with a transverse horizontal socket and apertures that communicate with this socket, the socket being engaged by an apertured shank 40 b of a bracket E, with which a tub-clamp F is pivotally connected. A rod G extends through registering apertures in both frame-standards and the bracket-shanks therein to hold said shanks in engagement with their 45 sockets. One end of rod G is shown upset to form a standard-opposing head, and the other end of said rod is shown as having a standard-opposing nut c run thereon; but both ends of the rod may be upset or other means 50 employed to prevent its automatic displacement.

The slots of the frame-standards are half-

round at their lower ends and bushed with sheet-steel bearings H for the journals of the lower wringer-roll I, each of these bearings 55 being provided with a standard-facing end flange d and upper horizontal flanges e, that engage transverse kerfs provided in said standards, open to the slots of same. The bushings serve to reduce friction to an extent that will obviate the use of lubricating material on the journals of the lower wringer-roll, and their flanges being opposed to ends of said roll the latter is prevented from having frictional contact with the wooden frame- 60 standards.

Engaging the slots in the frame-standards are metallic slides J K, each provided with lateral ribs f, that engage guide-grooves g, formed in said standards longitudinally thereof, and said slides are shaped at their lower ends to form bearings for the journals of the upper wringer-roll L, that is shown spur-gearied to the drive-shaft M, that has its bearings in slide K and a metallic bracket N, the 75 latter being made fast to a frame-standard by screws or other suitable means.

The drive-shaft is provided with the usual crank O, and sprocket-wheels P Q, fast on said drive-shaft and one of the lower wringer-roll 80 journals, are for engagement of a link belt, (indicated by dotted lines in Fig. 1,) the gearing as a whole being old in the art.

Sprocket-wheel P and a collar R of the drive-shaft oppose bearing-bracket N in opposite directions to prevent longitudinal play of said shaft.

An upper prolongation h of a barrel S has rocker-bearing on the rounded upper end of slide J, and another upper prolongation i has 90 similar bearing on trunnions (one of which is marked j in Fig. 1) extending from an upper inner corner of a bell-crank lever T, one arm of which is in rocker-bearing hook connection with the rounded upper end of slide K, its other arm being in like connection with the rounded end of an eye k at one end of a rod U, that extends through a compression-spring V and a spring-abutting washer m in said barrel, a tension-nut n being run on the screw-threaded 95 other end of the rod against the washer. Prolongation i of barrel S is necessarily forked to straddle lever T, each fork branch being in rocker-bearing contact with a trunnion j and 100

extended under a lateral lug *p* of said lever, one fork branch of the barrel, a lever-trunnion, and a lever-lug being shown in Fig. 1. A barrel-opposing set-screw *W* is adjustable 5 in the top bar *A* of the wringer-frame. The spring being inclosed in a barrel, it is protected from water, and hence less liable to rust under ordinary conditions to which a wringer is subjected, a compression-spring 10 having been found more efficient and durable than an expansion-spring. The tension of the spring is regulated by adjustment of nut *n* on rod *U* against washer *m*, and the spring-pressure is brought on the slides *J K* by down- 15 ward adjustment of the set-screw *W*, equal roll-pressure in the wringer being automatically maintained incidental to oscillation of bell-crank lever *T* when material thick or thin is run through the wringer.

20 Made fast to the frame-standards by screws or other suitable means are fender-brackets *X*, that support a spreader, the spreader in this case being a preferably-tubular arched bar *Y*, engaged at its ends by bosses *r* of said 25 brackets.

Having thus described my invention, what I claim as new, and desire to secure by Letters Patent, is—

1. A clothes-wringer having longitudinally-slotted frame-standards, bearing-slides guided 30 in the standard-slots, a bell-crank having

rocker-bearing connection with one of the slides, a barrel in similar connection with the bell-crank and other of said slides, a compression-spring in the barrel, a rod that being 35 in connection with said bell-crank extends through the spring, means in connection with the rod for tensioning the spring, and other means for exerting pressure on said barrel.

2. A clothes-wringer having longitudinally-slotted frame-standards, bearing-slides in the standard-slots provided with lateral ribs engaging guide-grooves provided in said standards, a bell-crank having rocker-bearing connection with one of the slides, a barrel in similar connection with the bell-crank and other of said slides, a compression-spring in the barrel, a rod that being 40 in connection with said bell-crank extends through the spring, means in connection with the rod for tensioning the spring, and other means for exerting pressure on said barrel.

In testimony that I claim the foregoing I have hereunto set my hand, at Muskegon, in 45 the county of Muskegon and State of Michigan, in the presence of two witnesses.

MAXIMILLIAN P. JANISCH.

Witnesses:

MABEL R. RODGERS,
JOHN Q. ROSS.
